BEND OF PIPE FOR EXHAUST SYSTEMS

Paul V. Gregg, Racine, Wis., assignor to Walker Manufacturing Company, Racine, Wis., a corporation of Delaware

Filed Nov. 25, 1966, Ser. No. 4,812

Term of patent 14 years

(Cl. D14—6)

FIGURE 1 is a top view showing the inside of a bend of pipe for exhaust systems embodying the design of this invention; and

FIGURE 2 is a side elevation of the bend of pipe for exhaust systems shown in FIGURE 1.

Both ends of the bend of pipe for exhaust systems shown in FIGS. 1 and 2 are fragmentarily shown for convenience of illustration to indicate indeterminate length.

I claim:

The ornamental design for a bend of pipe for exhaust systems, substantially as shown and described.
